RADIO DIRECTION FINDING APPARATUS

Charles William Earp, London, England, assignor to International Standard Electric Corporation, New York, N. Y.

Application October 15, 1937, Serial No. 169,198
In Great Britain February 23, 1937

10 Claims. (Cl. 250—11)

This invention relates to methods of and apparatus for giving a direct indication of the direction and/or polarisation of waves.

An object of the invention is the provision of such a device which is more simple in construction and more efficient in operation than those heretofore in use.

According to one feature of the invention signals received by two or more wave collectors are modulated with different wave-forms and the resultant modulation envelopes and the original modulating wave forms are used for operating an indicating device. The indicating device may comprise a cathode ray oscilloscope or an 15 electro-mechanical device such as a dynamometer.

According to a further feature of the invention three or more wave collectors are provided and the signals picked up from at least two 20 of them are modulated before all are combined, the modulation envelope of the combined signals being used together with the original modulating wave-forms for the determination of the direction and/or polarisation of the waves.

25 These and other features of the invention will be clear from the following description taken in conjunction with the accompanying drawings Figs. 1 to 4 of which show four embodiments of the invention.

30 Reference should first be made to Fig. 1 which shows schematically the arrangement according to the invention in its most general form. An aerial system A.E.W. which gives optimum sensitivity for east-west signals picks up 35 a signal the strength of which is proportional to $\cos \theta$ where θ is the bearing of the transmitting station measured anti-clockwise from east. This signal $(e \cos \theta)$ is applied to a modulating device M.E.W. where it is modulated by a wave 40 form $f(t)$ generated by the modulating generator G.E.W. the output from the modulating device M.E.W. is $\mu e \cos \theta f(t)$. A second aerial system A.N.S. which gives optimum sensitivity for north-south signals picks up a signal the strength of which is proportional to $\sin \theta$, which 45 is applied to a second modulating device M.N.S., where it is modulated by a different wave form $f'(t)$ by a modulating generator G.N.S. The output from the modulating device M.N.S. is $\mu e \sin \theta f'(t)$. The outputs from the modulating devices M.E.W. and M.N.S. are combined in an amplifier A with the pick-up K_e from a non-directional antenna A.N.D. After detection in a detector D the output from D is the modulation envelope of the signal K_e produced by the mod-

ulated outputs from the modulating devices M.E.W. and M.N.S.

The modulation envelope is applied to an indicator I, of which two types are described later, to which is also applied the wave forms $f(t)$ and $f'(t)$. A comparison of the modulation envelope with $f(t)$ and $f'(t)$ in the indicator gives the bearing of the transmitting station as will be described later.

Fig. 2 is, in principle similar to Fig. 1, but the 10 aerial systems A.E.W. and A.N.S. are each connected to a modulator ME, MW, and M.N, M.S of the balanced type giving true north-south and east-west symmetry of circuit.

Fig. 3 shows a practical embodiment of the 15 invention. Heptode valves VE, VW, VN and VS, respectively in balanced relation are employed in known manner as combined modulators and low frequency oscillators, the inner electrodes of the pairs of valves constituting low 20 frequency oscillators. The plates of all the four valves together with the output from a non-directional antenna A.N.D. are connected in parallel to an input of amplifier A.

The resultant wave forms are indicated above 25 the various portions of the amplifier-detector circuit. In the amplifier A, a symmetrically modulated high frequency wave is shown. After detection and filtering in detector D, the low frequency wave is amplified in a low frequency 30 amplifier L.F. and passed through a limiting device VL which produces a square wave form, the vertical sides of which correspond to the crossing of the low frequency wave through zero amplitude. The limiting device VL is of any 35 suitable type and in the form shown comprises a valve provided with a high value grid leak so that positive pulses are sharply limited by grid current and negative half cycles are limited by the bottom bend of the anode current grid voltage 40 characteristic.

The output of the valve VL is passed through a critically-damped transformer, in which the sudden changes of current produce alternate positive and negative peaks in the secondary 45 winding, which are applied to a valve VD biased to cut-off. Positive peaks only thus appear in the plate circuit and these appear in the wave form indicated as sharp pulses of plate current.

The peaky wave form so produced gives an 50 exact indication at every other instant at which the outputs from VE, VW, VN, VS total zero. It will be noted that every successive instant is not indicated since half the peaks are suppressed by the device VD.

If, now, the wave form of one oscillator is applied to the X deflector plates of a cathode ray oscilloscope O, and the wave form of the other oscillator is applied to the Y deflector plates, 5 and the peaky wave form from the device VD is employed to control the brilliance of the spot, for example, by controlling the grid of the oscilloscope and causing the spot to appear only at the peaks, then a straight line from the centre of the scale, pointing in the direction of the transmitting station, will be indicated on the oscilloscope as will now be demonstrated.

Referring again to Fig. 1, modulating generator G.E.W. produces a wave-form $f(t)$. This 15 wave form is applied as $-f(t)$ to the Y deflector plates of the oscilloscope causing a "y" or north deflection of $-f(t)$. Modulating generator C.N.S. has a wave form $f'(t)$ which is applied to the X deflector plates causing an "x" or east deflection of $f'(t)$. The input to modulator M.E.W. is $e \cos \theta$ from antenna A.E.W. and $f(t)$ from generator G.E.W. The output of this modulator is $\mu e \cos \theta f(t)$, the product of these components. Similarly the output of modulator M.N.S. is $\mu e \sin 20 \theta f'(t)$. The outputs from the modulators M.E.W. and M.N.S. are added together with the pick up Ke from the non-directional antenna A.N.D. If Ke is greater than

$$\mu e \sqrt{2}$$

30 then this signal is modulated symmetrically (and never to zero) by $\mu e \cos \theta f(t) + \mu e \sin \theta f'(t)$.

The instantaneous zero-amplitude of modulation of the detected and filtered signal, which is 35 indicated at the input of tube VD in Fig. 3 by sharp peaks, occurs when $\mu e \cos \theta f(t) + \mu e \sin \theta f'(t) = 0$, i. e. when

$$\tan \theta = \frac{-f(t)}{f'(t)} = \frac{y}{x}$$

40 The y axis of the oscilloscope is understood to be represented by a line on the surface of the oscilloscope screen perpendicular to the Y deflector plates so that the y axis will represent the path traced by the oscilloscope spot if an alternating potential is applied to the Y plates only. The x axis is then a similar line related to the 45 X plates. Since the waves f , f' , applied to the plates are different in wave form, for example in frequency, the pattern traced if the spot were 50 effective at all times would vary so as to cover the face of the screen with a given pattern. Since the peaks occur at the time when the ratio

$$55 \quad \frac{y}{x} = \frac{-f'(t)}{f(t)}$$

and only at this time is a spot indicated on the oscilloscope screen, it is clear that the screen will only be illuminated at points where the particular ratio of deflections x and y satisfy this 60 condition. However, since the frequencies are different the relative ratios of deflecting potentials is continuously varying and at the points where they satisfy the above relationship a point 65 of light will be observed. For example, at the time antennae AEW and ANS are at equal angles to the source, the ratio

$$\frac{y}{x}$$

70 which will satisfy the conditions as outlined with the structure of Fig. 3, is one in which $\theta = 45^\circ$. At the same time the peaks will occur to control the spot of light, a line will be indicated on the 75 oscilloscope at 45° to the x and y axes of the

screen which corresponds to the direction of the source.

Thus, if the oscilloscope operates only when the instantaneous modulation amplitude equals zero, then the diagram will be a straight line 5 pointing in the direction of the transmitter.

By the use of different modulating wave-forms the whole of the oscilloscope screen is scanned and the direction is indicated by a line which extends to the edge of (or even beyond) the circular 10 compass scale.

The particular method of selection of zero amplitude of modulation shown in Fig. 3 picks out alternate zeros, and the line drawn on the oscilloscope extends in one sense only from the centre 15 of the screen, thus giving no ambiguity of sense of the signal.

If the non-directional signal Ke is omitted the envelope of the high frequency wave passed through the amplifier A gives twice as many 20 maxima and twice as many minima as for the case when a non-directional antenna is used and Ke is added. The production of peaks by the same method as before does not indicate zero amplitude from the modulators, but a mean amplitude. These peaks, however, may still be used to indicate direction on the oscilloscope. In this case, the number of peaks being doubled, direction but not sense of the signal will be indicated.

30 As shown in Fig. 4 the coils of the low frequency oscillator modulator valves V.N.S. and V.E.W. may be connected as the field coils FC1—FC4 of a dynamo-meter indicating instrument. When the oscillator portions of V.N.S., 35 V.E.W. operate at frequencies f_1 and f_2 , then modulation of the signal is produced at each of these frequencies. This produces a field which varies with time since the potentials vary with time under control of f_1 and f_2 . If, now, the output from detector D is taken to a search coil S suspended in the field of the coils FC1—FC4, 40 each oscillator exerts a couple on the search coil S according to the strength of the modulation at f_1 (for one oscillator) and f_2 (for the other oscillator). The total effective field upon the search coil, varies then not only with the impressed field on the field coils but also in proportion to the current in the search coil. Thus, the 45 direction is indicated by the resultant field forces in a manner analogous to that more fully explained in connection with Fig. 3. The result is that the search coil S takes up a position corresponding to the direction of the incoming signal. It will be noted that in this arrangement the 50 output from the detector D is applied directly to the search coil S. The deliberate distortion of the wave form employed for the oscilloscope indication described with reference to Fig. 3 is not necessary. It will be noted that simple modulators are employed in Fig. 4. Although the 55 symmetrical circuit as used in Fig. 3 is likely to give the best results in practice there is no theoretical reason why two simple modulators only should not be used.

60 The invention is of course not limited to the precise arrangements described and many modifications will readily occur to be versed in the art. The modulation of the signals is conveniently carried out by heptode valves, but any 65 modulating device could be used including both electrical and mechanical methods. For electrical methods, metal rectifiers, diodes, triodes, tetrodes, pentodes, etc., are obvious solutions. The modulating wave forms are most conven- 70

iently provided by simple low frequency oscillators but any wave forms could be used. Moreover, whilst two methods for the comparison of the "modulation envelope" with the modulating wave have been described numerous other methods could obviously readily be evolved.

5 The directional aerials A.E.W., A.N.S. may be loop aerials but larger structures could be used, such as are employed, for example, in Ad-
10 cock direction finding systems. Instead of the conventional north-south and east-west aerial systems four completely separate non-directional aerials may be used with individual associated modulators.

15 The aerials A.E.W. and A.N.S. are not necessarily disposed at right-angles. They have been described as being at right-angles only because it is more convenient to design an indicating device with controlling forces operating at right angles. The loops could be arranged at any angle provided a corresponding disposition were given, for example, to the field coils FC¹—FC⁴ in Fig. 4.

20 Any type of amplifier and detector may be used. The use of a single amplifier and detector is convenient but two separate amplifiers and detectors could be used, one for the north-south signal and the other for the east-west signal.

25 An exact balance of the two directive aerial systems is not necessary, nor an exact balance of the two modulators. A compensation for unbalance may be effected by controls operating upon the amplitude of signals from one antenna system, sensitivity of a modulator, a relative 30 sensitivity of north-south and east-west indications on the indicating device, or the amplitude of input to the indicator of either modulating wave forms. A calibrating signal may be used for effecting a balance of the system.

35 40 Any "site error" or error due to unbalance in the indicating device may be compensated for as described in the preceding paragraph, by mechanical rotation of either of the aerial systems, or by adjustment of direction of the field 45 coils in Fig. 4 or the deflector plates of the oscilloscope in Fig. 3. For example, the north-south bearing is corrected on the indicating device by rotation of the east-west aerial particularly if this is a loop. Similarly the exact east-
50 west bearing is corrected by rotation of the north-south aerial. Any remaining errors which may be evident at NW, SW, SE or NE may now be compensated by adjustment of one modulating wave-form input to the indicating device. When 55 these adjustments have been made, a small octantal error, only, is possible.

The broad principle of the invention as defined by the appended claims is also applicable to systems for automatically indicating the polarisation of incoming electromagnetic waves, and for automatically indicating the direction of sound waves.

What is claimed is:

1. Apparatus for giving a direct indication of the direction of waves, comprising at least two wave collectors, means for producing two modulating waves of different wave form, means for modulating the signals received by one of said collectors with one of said modulating waves and the signals received by the other of said collectors with the other of said modulating waves and for combining said modulating waves and for controlling jointly by said combined modulating waves and said modulating waves, and responsive to the relation between said combined modu-

lated signals and said modulating waves for indicating the relative strengths of the signals received by said collectors.

2. A device for giving a direct indication of the direction of incident electromagnetic waves, comprising two directional wave collectors the directions of maximum pick-up of which are arranged at an angle, means for producing two modulating waves of different wave forms, means for modulating the signals received by one of said wave collectors with one of said modulating waves and the signals received by the other of said wave collectors with the other of said modulating waves and for combining said modulated signals, and means controlled jointly by said combined modulated signals and said modulating waves, and responsive to the relation between said modulated signals and said modulating waves for indicating the relative strengths of the signals received by said wave collectors.

3. Apparatus for giving a direct indication of the direction of incident electromagnetic waves, comprising two directional wave collectors the directions of maximum pick-up of which are arranged at an angle, means for producing two modulating waves of different wave form, means for modulating the signals received by one of said wave collectors with one of said modulating waves and the signals received by the other of said wave collectors with the other of said modulating waves and for combining said modulated signals, means for deriving a control signal from said combined modulated signals, a cathode ray oscilloscope for producing a spot of variable brilliancy and controllable position, means for controlling the brilliancy of said spot by said control signal, and means for controlling the position of said spot by said modulating waves.

4. Apparatus for giving a direct indication of the direction of incident electromagnetic waves, comprising at least two directional wave collectors the directions of maximum pick-up of which are arranged at an angle, means for producing two modulating waves of different wave form, means for modulating the signals received by one of said wave collectors with one of said modulating waves and the signals received by the other of said wave collectors with the other of said modulating waves and for combining said modulated signals, means for deriving a control signal from said combined modulated signals, a dynamometer having field coils and a search coil movable relative thereto, means for energizing said search coil with said control signal, and means for energizing said field coils with said modulating waves.

5. Apparatus as claimed in claim 2, further comprising a non-directional wave collector and means for combining the signals received by said non-directional collector with said modulated signals.

6. Apparatus as claimed in claim 2, wherein said means for modulating the signals received by one of said collectors with one of said modulating waves and the signals received by the other of said wave collectors with the other of said modulating waves and for combining said modulated signals, comprises a balanced thermionic modulator for each of said signals to be modulated, and means for combining the outputs of said modulators.

7. Apparatus as claimed in claim 2, wherein said means for modulating the signals received by one of said collectors with one of said modu-

lating waves and the signals received by the other of said wave collectors with the other of said modulating waves and for combining said modulated signals, comprises a thermionic valve for each of said signals to be modulated, connections whereby each of said valves operates as a combined oscillator and modulator, and means for combining the outputs of said valves.

8. Apparatus as claimed in claim 3, wherein 10 said means for deriving a control signal from said combined modulated signals comprises means for detecting said combined modulated signals, and means for producing from said detected signals a peaky wave form having peaks corresponding 15 to alternate instants of zero amplitude of the envelope of the combined modulated signals.

9. Apparatus as claimed in claim 3, wherein said means for deriving a control signal from said combined modulated signals, comprise 20 means for detecting said combined modulated signals, means for modifying said detected signals to produce a square wave form, means for

converting said square wave form into a peaky wave form, and means for passing alternate ones only of said peaks.

10. Apparatus for giving a direct indication of the direction of incident electromagnetic waves, comprising two directional wave collectors and a non-directional wave collector, means for producing two modulating waves of different frequency, means for modulating the signals received by one of said wave collectors with one 10 of said modulating waves and the signals received by the other of said wave collectors with the other of said modulating waves and for combining said modulated signals, means for combining both of said modulated waves with each 15 other and with the signals received by said non-directional collector, and means responsive to the relation between said combined signals and said modulating waves for indicating the relative strengths of the signals received by said directional wave collectors.

CHARLES WILLIAM EARP.
